UNITED STATES PATENT OFFICE.

ROBERT M. SCANLAN, OF TOLEDO, OHIO, ASSIGNOR OF ONE-HALF TO JOHN B. SHEPLER, OF TOLEDO, OHIO.

MULTIPLE-PLY-PAPER-BOARD-MAKING MACHINE.

1,018,588.

Specification of Letters Patent.

Patented Feb. 27, 1912.

Application filed November 7, 1910. Serial No. 591,063.

To all whom it may concern:

Be it known that I, ROBERT M. SCANLAN, a citizen of the United States, and a resident of Toledo, in the county of Lucas and

5 State of Ohio, have invented a certain new and useful Multiple-Ply-Paper-Board-Making Machine; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

10 15 My invention relates to machinery of the type employed for the making of multiple-ply paper, card-board, binders' board or the like.

The machines heretofore used for such purpose, so far as I am aware, have employed cylinders upon which a sheet or web of pulp is wound until the paper or board being made is of the desired thickness. When such operation has been performed 20 25 30 the paper or board thus made is removed from the cylinder and is then longitudinally severed and rolled out into flat sheet form. As the diameter of the successive plies naturally increase as one winds upon the other it is apparent that when the board is flattened the greater length of the outer plies will cause wrinkles to occur in the outer side of the board, which wrinkles in the rolling operation are flattened and pressed into the 35 board. It is impossible, however, to entirely remove the roughness occasioned by such wrinkles, thus necessarily leaving the outer side of the board with a rough surface which renders it impractical for certain uses.

40 45 50 The object of my invention is to overcome the objections to the making of multiple-ply board in cylinder form and then flattening the same, by the provision of a machine which will make a flat board of as many plies as desired and so operate on the board that it is delivered from the machine in continuous sheet form and in condition to be cut into sheets of the desired size.

A further object of my invention is the provision of a simple and efficient machine of this class which will enable the outer ply of a board to be made of the same or of different color and of colors which are dif-

ferent from the inner or body ply thereof, thus enhancing the practicability and commercial value of machines of this class and making the manufacture of multiple-ply board both simple and economical.

55 60 65 The invention is fully described in the following specification and while in its broader aspect, it is capable of embodiment in numerous forms, a preferred embodiment thereof is illustrated in the accompanying drawings, in which,—

Figure 1 is a side elevation of a machine embodying my invention with a greater part thereof in vertical longitudinal section. Fig. 2 is an enlarged section of one of the ply affixing units of the machine with the associated part of the machine. Fig. 3 is an end view thereof with a portion of the pulp carrying screen broken away. Figs. 4 and 5 are enlarged details of the drive mechanism of the machine. Fig. 6 is an enlarged top plan of one of the ply affixing units of the machine with a portion of the screen broken away, and Figs. 7 and 8 are enlarged sectional details of a portion of the pressing and water-extracting rolls of the machine.

65 70 75 80 85 90 95 100 105 Referring to the drawings, 1, 1, designate the frame sides of a machine embodying my invention, between which sides are mounted upper and lower sets of pressing and water-extracting rolls 2, and intermediate sets of preferably smaller pressing and water-extracting rolls 3. At least one of the rolls of each of these sets is mounted for adjustment toward and away from its companion, which adjustment is controlled in each case by an adjusting screw 4. Each set of rolls 3 is shown in the present instance as comprising one perforated or water-extracting roll while the other roll has a solid or imperforate periphery to adapt it to press the intermediate material to the perforated roll to squeeze the water therefrom through the perforated roll. The perforated and solid rolls of the sets 3 are preferably arranged in alternate order as shown. The rolls 2 and the perforated ones of the sets 3 are of substantially the same construction and are for the same purpose as the water extracting rolls described and claimed in my United States Letters Patent No. 741,980, dated October 20, 1903, and will therefore not be described in detail. The liquid is carried off from the rolls by

troughs 5 disposed therein and delivered to a drainage pipe 6 at one side of the machine.

Two belts or endless aprons 7, of felt or other suitable material pass between the sets 5 of pressing and water extracting rolls 2 and 3 and pass in opposite directions therefrom around suitably arranged idler and take-up rolls 8, and have portions 7' thereof guided adjacent the top of the machine for substantially horizontal movements toward the upper set of rolls 2 by a part of the idler rolls 8 as shown. The aprons 7 after leaving the lower set of rolls 2 are shown in the present instance as passing between a final set of compressing rolls 9, which set of rolls also serves as the drive-rolls for the aprons. For this purpose the rolls are geared together by gears 10, see Figs. 4 and 5, and on the shaft of one roll is mounted a pulley 11, which is shown as 15 being driven by a belt 12, which in turn is driven by a motor 13, or in any other suitable manner.

Arranged above the horizontal portion 7' of each apron 7 and supported by the frame 25 sides 1, or in any other suitable manner, are a plurality of tanks 14 comprising parts of separate ply affixing units of the machine. Each tank 14 has an endless screen or perforated belt 15 associated therewith, such screen being guided for movement around the tank and down into the same by idler rolls 16, one at least of which is mounted for adjustment in its bearings to take up slack in the screen, and is shown as having 30 an adjusting screw 17 for such purpose. The screen 15 travels in the direction indicated by the arrow or at its lower side in the same direction as the horizontal portion 7' of the associated apron 7 and is guided to 35 enter the tank at one side thereof and thence to travel upwardly on an incline over the opposite side of the tank as shown. The inclined portion of the apron 15 passes over a correspondingly inclined table or platform 40 18 in substantial contact therewith, and this table or platform is provided with sets of perforations 19 and 20, which extend transversely thereof throughout its width. The set of perforations 19 open into a chamber 45 21 within the tank 14 and provide the only means of exit for liquid from the tank, such liquid flowing from the chamber 21 through one or more pipes 22 in its bottom. The pipes 22 lead into a manifold 23, 50 which has connection through a pipe 24 with a pipe 25, which has its discharge into the associated tank 14 above the table 18 at a point to the rear of the set of perforations 19. A forced circulation is created through 55 the tank 14, chamber 21 and pipe 24 in the present instance by a centrifugal pump 26, which is interposed in the pipe 24. In order that the circulation of liquid through the tank 14 and its chamber 21 may be distributed throughout the length of such chamber,

a plurality of exit pipes 22 are provided for such purpose, thus preventing stagnation of liquid at any point within the chamber 21.

The pipe 25 into which the pipe 24 has its discharge has a branch 27 which leads from 70 and forms a discharge pipe from a paper pulp vat 28. The pulp from the vat 28 and the water passing through the pipe 24 commingle within the common discharge pipe 25 and are discharged together into a distributing trough 25' from which they flow over the side thereof upon the screen 15 into the tank. As the screen in its travel passes over the set of perforations 19 in the table the suction created by the forced circulation of 80 liquid through the tank 14, chamber 21 and pipe 24 draws the water from the screen and leaves a layer of pulp evenly distributed over the screen surface.

If binder or other board having its faces 85 or outer sides of a different color from the interior thereof is manufactured, each end tank should have its own individual circulating pipe 24 as such liquid is colored and would effect a coloring of the liquid in the 90 intermediate tanks if it were permitted to commingle therewith. For this reason the end tanks 14 of the machine are shown as having individual water circulating pipes, while the water circulation of the intermediate tanks is through a common pump 26.

The water line of each tank 14 is at a point which is level with the upper edge of the set of perforations 19, as indicated by dotted line in Fig. 2, thus placing the second set of perforations 20 above the water line. The perforations 20 open into a suction chamber 29 which has communication through a pipe 30 with a vacuum pump 31, which is shown as being driven in the present instance by a motor 32. The pipe 30 forms a manifold with which the chambers 20 of all the vats associated with the machine are shown as communicating. As a screen 15 and adhering pulp passes over the set of perforations 20, the air suction created through such perforations and chamber 29 tends to draw from the screen a large portion of the remaining liquid carried thereby so as to very materially reduce the moisture carried by the pulp and screen after passing from the tank. As each screen 15 passes under its tank its outer pulp carrying side is pressed against the subjacent portion 7' of the apron 7 by one of the guide rolls 16, which roll is designated 16', thus causing the pulp to release its hold upon the screen and to adhere to the surface of the apron 7, or, if it be an intermediate ply of the board, to adhere to the ply or layer of pulp which was placed upon the apron by the preceding screen of the machine. A roll 33 acts upon the under side of the apron 7 beneath the roll 16' to cooperate with such roll to hold the apron 7 and screen 15 in contact at the 115 120 125 130

point of transfer of the pulp layer from one to the other thereof as above described. The roll 33 is held in yielding contact with the apron 7 due to its being hung at the ends of lever arms 34 which are pivoted to associated parts of the frame sides 1 and connected at the ends thereof which are opposed to the roll 33 to weighted arms 35 by links 36. The weighted arms 35 are in turn shown as being pivoted to fulcrum links 37 as indicated in Fig. 2. The rolls 33 are preferably perforated to form liquid extracting rolls so that the liquid which would otherwise back up between the apron 7 and screen 15 to the rear of the rolls 16' and 33 will be drained off to a large extent through the rolls 33. This action is also facilitated by slightly inclining the portions 7' of the aprons 7 from their inner ends outwardly as indicated, thus causing the liquid which is pressed from the pulp carried by the screen 15 to flow toward the rolls 16' and 33 instead of rearwardly therefrom.

It will, of course, be understood that as many tanks 14 and their associated pulp applying parts may be employed as the thickness or number of plies of the board being manufactured may require, and that the horizontally disposed portions 7' of the aprons 7 may be of suitable length to accommodate the number of tanks used.

In the operation of my invention the running of the motor 13 drives the set of rolls 9, which in turn act upon and drive the aprons 7, 7 in the directions indicated by the arrows. While the pulp applying screens 15 may be run in any suitable manner as desired they are shown in the present instance as being driven by reason of their frictional contact with the aprons 7. The pulp being free to flow from the vats 28 to the respective tanks 14 and the different mechanisms of the machine being in operation, the pulp and water flow together into the discharge pipe 25 where they commingle and are discharged into the distributing trough 25' which is disposed across the top of the inclined table 18 within the associated tank 14 and to the rear of the set of perforations 19 in such table. The pulp and water which flow from the trough 25' are deposited upon the portion of the associated screen 15, working over the table 14. As the screen passes over the set of perforations 19, the water circulation through such perforations causes an evening of the pulp layer upon the screen and draws a part of the water therefrom. As the screen emerges from the liquid in the tank 14 and passes over the set of perforations 20 the air suction through such perforations draws a large portion of the water which adheres to the pulp and screen therefrom, and the pulp layer is then carried by the screen to the subja-

cent apron 7 between the rolls 16' and 33. The pressing of the screen 15 and apron 7 together by the rolls 16' and 33 causes the pulp layer carried by the screen to be transferred therefrom to the apron. As the layers of pulp thus deposited upon the aprons 7 by the outer end screens 15 of the machine are carried toward the set of pressing rolls 2, they pass under the screens 15 of the other pulp applying units in the order of their arrangement. The layers of pulp carried by such screens are successively applied thereto one on top of another and as the aprons pass down between the sets of pressure and water-extracting rolls 2 and 3 the multiple-ply pulp or board carried by the two aprons are pressed together to form a single sheet of binders' board or the like. The passing of the pulp sheet between the rolls 2 and 3 in addition to closely pressing the layers of the board together, extracts the water therefrom so that the sheet when delivered from the final set of rolls contains a minimum of moisture. After passing between the drive rolls 9, the pulp sheet is fed to a cutting mechanism, not shown, by which it is severed into sheets of the desired size.

The machine shown is provided with four pulp applying units, two in association with each apron 7, thus adapting the machine for the manufacture of a four-ply board. It is understood, however, that the invention is not restricted to any particular number of pulp applying units as the number of the same depends upon the thickness of the board being manufactured. Should it be desired to manufacture a board having its outer sides either of the same or of different colors, but different in color from the inner plies or layers, the pulp in the end vats 28 may be of the desired color or colors and the pulp in the intermediate vats 28 be in its natural state or colored to suit the desired shade of the intermediate layers of the board. The thickness and proportional distribution of the pulp layer upon a screen 15 is regulated by the water circulation through the associated pipe 24, as the regulation of the valves in the pipes 22 leading to the manifold 23 will effect a change in the thickness of the pulp layer on the screen 15.

The applying of the pulp layers to the upper sides of the aprons 7, 7 instead of to the under side thereof as has been the case with paper making machines heretofore used, so far as I am aware, is a very important feature of my invention. With the types of machines formerly used, or those in which the pulp layers are applied to the under side of an apron, the weight of such layers causes them to frequently drop from the apron, thus necessitating a stopping of the machine to replace the pulp layers in adherence to the under side of the apron.

With applicant's construction it is impossible for the pulp layers to drop from engagement with the aprons as such layers lie on the top surfaces of the aprons until they have passed with the aprons between the compressing rolls 2 and 3. This manner of securing the pulp layers to the aprons is also found to prolong the life of such aprons, and as these aprons are quite expensive the prolonging of the life thereof is an important feature.

I wish it understood that my invention is not limited to any specific construction or arrangement of the parts except in so far as such limitations are specified in the claims.

Having thus described my invention, what I claim as new and desire to secure by Letters Patent, is,—

20 1. In a machine of the class described, the combination of two endless aprons having horizontally moving portions and contiguous vertically moving portions, means guiding the movements of said aprons and 25 serving to press the contiguous vertical portions thereof together, and means for applying pulp in layer form upon the tops of the horizontal portions of the aprons in position for such layers to pass with the aprons 30 between the pressing portions of said guide means whereby such layers are united in a single multiple ply sheet.

2. In a machine of the class described, the combination with a movable apron, of a 35 tank having a liquid chamber, a liquid circulating chamber and a vacuum chamber, the circulating and vacuum chambers each having a top provided with perforations opening into each of said chambers, an endless perforate belt guided for movement 40 around said tank with a part in contact with said apron and a part extending down into the tank and passing over said top substantially in contact therewith throughout 45 its length, means for discharging a liquid pulp upon the portion of said belt passing over said top, means for creating a circulation of liquid through the belt, one set of said perforations and the circulating chamber, and means for creating a vacuum with- 50

in the other of said chambers to create a suction through the perforations leading thereto.

3. In a machine of the class described, the combination with a movable apron, of a 55 tank having a water circulating chamber and an air circulating chamber therein, the tops of said chambers being inclined and standing in a common plane and each having perforations to the respective chambers, 60 an endless perforate belt guided for movement around the tank with its outer side in contact with said belt at a point in its movement and with a portion guided for movement down into the tank and over the tops 65 of said chambers in close proximity thereto, means for discharging matter into the tank over said belt below the said perforations, means for causing a circulation of water through the water circulating chamber and 70 the perforations in its top, and means for creating a circulation of air through said air chamber and the perforations in its top to act to extract liquid from the belt as it passes thereover.

75 4. In a machine of the class described, the combination of a pair of oppositely movable endless aprons, a plurality of sets of pressure and liquid extracting rolls acting on the aprons to press portions of the 80 same together and extract liquid therefrom, idler means for guiding the actions of said aprons, means for driving the aprons, and at least one pulp applying unit associated with each apron for applying pulp in layer 85 form thereto in position to pass with the aprons between said pressure and liquid extracting means, said units each comprising a tank, an endless pulp applying member movable around said tank and into the same and in contact with the associated apron, and means for discharging liquid pulp within the tank and upon said member.

In testimony whereof, I have hereunto signed my name to this specification in the 95 presence of two subscribing witnesses.

ROBERT M. SCANLAN.
